United States Patent Office

Des. 177,649
Patented May 8, 1956

177,649

COMBINED SINK AND TABLE TOP

Jacques Stanitz, Warren, Ohio, assignor, by mesne assignments, to American Radiator & Standard Sanitary Corporation, New York, N. Y., a corporation of Delaware

Application February 17, 1953, Serial No. 23,652

Term of patent 14 years

(Cl. D4—2)

Fig. 1

Fig. 2 is a front elevation thereof; and

Fig. 3 is a side elevation thereof.

I claim:

The ornamental design for a combined sink and table top, substantially as shown
